United States Patent

Des. 241,360
Patented Sept. 7, 1976

241,360

TOY JET ENGINE

James J. Scozzafava, P.O. Box 40152,
Washington, D.C. 20015

Filed Dec. 23, 1974, Ser. No. 536,937

Term of patent 7 years

Int. Cl. D21—01

U.S. Cl. D34—15 HR

FIG. 1

FIG. 2

FIG. 3

FIG. 4

FIG. 5

FIG. 1 is a front perspective view of a toy jet engine showing my new design;

FIG. 2 is a side elevational view thereof shown on an enlarged scale;

FIG. 3 is a bottom plan view thereof;

FIG. 4 is a front elevational view thereof; and

FIG. 5 is a rear elevational view thereof.

I claim:

The ornamental design for a toy jet engine, as shown and described.
